LED Canopy Light by Adiding; ASIN:B076M5XW2G. Date first available at amazon.com—Oct. 20, 2017. (Year: 2017).*

* cited by examiner

Primary Examiner — Clare E Heflin(74) *Attorney, Agent, or Firm* — Ladas & Parry LLP(57) **CLAIM**

The ornamental design for an LED canopy light, as shown and described.

DESCRIPTION

FIG. 1 is a front elevational view of a LED canopy light showing my new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front, top, right perspective view thereof;

FIG. 8 is a front, bottom, left perspective view thereof.

The broken lines shown on FIG. 6 depict portions of the LED canopy light that form no part of the claimed design.
